CLIP ASSEMBLY

Hans A. Bauer, Prairie View, Ill., assignor to
Autopoint Company, Chicago, Ill., a corporation
of Illinois

Application April 18, 1946, Serial No. 663,051

5 Claims. (Cl. 24—11)

1

The present invention relates to a clip for fountain pens, mechanical pencils and the like, and especially to a novel clip construction and assembly and to the manner of locating and mounting the clip in the cap of a fountain pen or mechanical pencil.

The invention comprehends a novel clip and resilient mounting therefor so constructed and arranged as to facilitate the assembly of the clip by a simple operation. It further permits the ready removal or replacement of the clip or spring mounting, should the occasion require, without the necessity of returning the cap to the manufacturer.

A further object of the present invention is the provision of a novel spring means for exerting the desired tension upon the clip, and in the novel means and manner of applying or positioning the spring in the cap. This spring in addition to applying the desired tension, also anchors and retains the clip in its centered, operative position.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while there is shown therein a preferred embodiment, it is to be understood that the same is susceptible of modification and change, and comprehends other details, arrangements of parts, features and constructions without departing from the spirit of the invention.

In the drawing—

Fig. 1 is a view, part in side elevation and part in vertical cross-section, of a cap for a fountain pen, pencil or the like, and showing the novel clip applied thereto.

Fig. 2 is a fragmentary view in vertical cross section through the novel clip and cap assembly, the view being taken on the line 2—2 of Fig. 1.

Fig. 3 is a fragmentary perspective view of the cap.

Fig. 4 is a view in perspective of the cap sleeve.

Fig. 5 is a perspective view of the novel clip.

Fig. 6 is a perspective view of the spring or tension means for mounting and retaining the clip in the cap.

Fig. 7 is a view in side elevation of the spring and a tool about to receive the spring for mounting it in position.

2

Fig. 8 is a view in front elevation of the tool and spring received thereon and ready to be mounted in the cap.

Referring more particularly to the novel illustrative embodiment shown in the drawing, the invention comprehends a clip 1 disclosed as applied to the cap 2 of a pencil, fountain pen or similar article 3 adapted to be carried in or attached to the pocket or other part of the clothing. To prevent accidental or unintentional removal of the pen, pencil or the like from the pocket or other part of the clothing, the clip is adapted to yieldingly grip the material of the pocket or other support.

15 The present novel clip is provided with a shank 4 having at one end a rounded end or tip 5, and at its other end is provided with an arcuate-shaped part 6 adapted to be received in an arcuate-shaped slot 7 and conform to the slot and the 20 outer rounded contour of the upper end of the cap 2. In order to anchor the clip in the cap but permit limited movement of the rounded tip or end 5 from the body of the cap whereby the clip may be attached to a pocket or other support, this clip is provided with an irregularly 25 shaped lug or projection 8 adjacent the arcuate end 6 and adapted to extend inwardly into and be resiliently mounted in the interior of the cap by means of a spring 9.

30 To properly mount and fulcrum the clip in the cap, the latter at the ends of the slot 7 is bent or deformed inwardly to form flanges or projections 10 and 11, and within the cap is provided a sleeve 12. This sleeve is held therein by a tight 35 frictional fit with opposed portions of the upper end of the sleeve being bent inwardly and downwardly to provide inturned flanges 13 and 14 forming a pair of downwardly opening channels or grooves 15 and 16 below the flanges 13 and 14 which, in turn, abut the underside of the flanges 10 and 11 which provide a stop therefor.

40 As the slot 7 extends completely across the upper or outer end of the cap and to the same extent along either side, and the channels 15 and 16 in the sleeve 12 are also symmetrically disposed, the clip may be inserted at either side of the slot. After the clip has been mounted in its proper position with the end 17 of the arcuate part 6 abutting or seating upon either flange or 45 projection 10 or 11, the spring 9 is inserted or mounted in its proper position. This is accomplished from the interior of the cap preferably by means of a pronged or slotted tool A adapted to receive the spring in the manner shown in 50 Figs. 7 and 8 in which the upper end of each bi-

furcation of the tool is notched to engage the lateral projections or ears 18 and thereby lift and carry the spring into the upper end of the cap. To anchor the spring in position, the free end 19 thereof is first moved into a channel or recess 15 or 16 in the sleeve 12 and the bifurcated end 20 is moved or lifted beyond the lug or projection 8 on the clip and then moved laterally into a position above the upper edge 21 on this projection. Withdrawing or lowering the tool after the end 20 is positioned adjacent the upper edge 21 and in alignment therewith, permits this bifurcated end to span or bridge the thickness of the lug or projection 8 and become anchored thereon. A shoulder 22 on the lug limits the movement of the end 20 in one direction while the construction of the spring is such as to wedge this end into the corner as shown in Fig. 1.

When the spring is located in the assembled position shown in Fig. 1, the shank 4 and curved end or tip 5 on the clip may be withdrawn from the body of the cap under tension of the spring 9. This movement is guided and limited by the end 17 of the clip abutting against a flange or projection 10 or 11 of the cap, and the cam surface 23 on the projection or lug 8 riding over the adjacent flange 13 or 14 on the sleeve.

It will thus be seen that the invention comprehends a novel clip and mounting assembly that is composed of a minimum number of parts, is easily assembled or disassembled, and in which the clip is interchangeable. The cap need not be returned to the manufacturer should the owner desire to replace a clip and/or spring, but such replacement may be easily and quickly made by a retailer or one having a tool similar to tool A for removing or replacing the spring.

The cap, sleeve and clip may be of any metal or other material suitable for the purpose, and due to the novel construction and arrangement of the cap and clip assembly, the head of the clip may be inserted from either side of the slot and the clip may be mounted at either side of the cap. This greatly facilitates the manufacture and assembly of the parts and results in an appreciable saving in the cost of production.

Having thus disclosed my invention, I claim:

1. A clip and cap assembly for a pencil, pen or the like, comprising a hollow cap open at one end and closed at the other end except for a transverse slot extending through and completely across the closed end thereof and opening into the hollow interior, a clip having a curved tip at one end and an arcuate part at the other end conformably received within and projecting through the slot and provided with a depending lug projecting into the hollow interior of the cap, and a spring located wholly within the cap for mounting and retaining the clip in the cap and having one end anchored in the cap and the other end projecting over and anchored upon the depending lug for locking the arcuate part within the slot and urging the curved tip into gripping action with a pocket or other support upon which the clip is mounted.

2. A clip and cap assembly for a fountain pen, pencil and the like, comprising a hollow cap open at one end and closed at the other end except for a transverse slot extending across and completely through the closed end thereof and opening into the hollow interior of the cap, a clip having a shank projecting along the exterior of the cap and provided with a part at one end tensionally retained against the exterior of the cap

but readily withdrawn therefrom for securing the cap upon a pocket or other support, an arcuate part at the other end conformably received within the slot with the extreme end of the arcuate part disposed adjacent one end of the slot, and a projection depending from the arcuate part adjacent the other end of the slot and extending through the slot into the interior of the cap, and a spring located wholly within the hollow of the cap and insertable only through the open end for mounting and retaining the clip in the slot of the cap and having one end anchored in the cap and the other end anchored upon and interlocked with the projection for applying tension to the clip.

3. A clip and cap assembly, comprising a hollow cap for a fountain pen, pencil and the like open at one end and closed at the other except for a transverse slot extending through and across the closed end and opening for the length thereof into the hollow interior of the cap, a clip having a shank provided with a curved tip at one end, an arcuate head at the other end conformably received within and projecting through the slot and provided with a depending projection extending into the interior of the cap, and a curved leaf spring located wholly within the cap and adapted to substantially encompass the projection with one end anchored in the cap at one side of the projection and the other end bifurcated and projecting over and interlocking with the upper edge of the projection for detachably mounting the head in the cap and for applying tension to the clip.

35. 4. In combination, a hollow cap for a fountain pen, pencil and the like, said cap having a slot extending completely across the normally closed upper end of and opening into the hollow interior of the cap with the material of the cap at each end of the slot turned inwardly to provide thereat a pair of oppositely disposed shoulders, a sleeve mounted within the cap and provided with oppositely disposed inturned flanges abutting the underside of the shoulders in the cap, a clip having a shank provided with an arcuate part conforming to and received within the slot in the cap and with its extreme end seating upon either of said shoulders, a depending projection on said part spaced from the end and projecting through the slot into the interior of the cap and sleeve, and a leaf spring located within the interior of the cap and sleeve and having one end engaging and anchored beneath the inturned flange on the sleeve and shoulder at the end of the slot opposite that against which the extreme end of the arcuate part seats and the other end of the spring anchored onto the projection for mounting and retaining the clip in assembled relation and spring-biasing the clip whereby to apply tension to and resiliently urge the shank against the cap.

5. A clip and cap assembly for a fountain pen, pencil and the like, comprising a hollow cap open at its lower end and closed at the upper end except for a slot extending completely across and through this upper end and opening into the hollow interior of the cap, a shoulder provided at each end of the slot, a sleeve mounted within the cap and provided with oppositely disposed, inturned flanges in alignment with and abutting the shoulders in the cap, a readily removable and interchangeable clip having a shank, an arcuate head conformably received in and projecting through the slot into the hollow interior of the cap, said head having an end seating upon an adjacent shoulder of the cap and a depending lug

projecting into the interior of the cap and sleeve adjacent the other shoulder, and a leaf spring within the hollow interior of the cap and sleeve for urging the shank of the clip against the cap, said spring substantially encompassing the lug and having one end engaging the upper end of the lug and the other end anchored within the adjacent inturned flange on the sleeve for applying tension to the clip and urging the shank toward the cap.

10
